SACHUSETTS.

RATCHET-WRENCH.

1,167,948.

Specification of Letters Patent. Patented Jan. 11, 1916.

Original application filed April 25, 1910, Serial No. 557,384. Divided and this application filed November 7, 1911. Serial No. 658,979.

To all whom it may concern:

Be it known that we, LAROY S. STARRETT and JOHN A. ADELL, both citizens of the United States, residing both at Athol, county 5 of Worcester, Commonwealth of Massachusetts, have invented certain new and useful Improvements in Ratchet-Wrenches, of which the following is a specification.

This invention relates to wrenches and 10 particularly to an extensible wrench for use in places otherwise inaccessible. The particular wrench shown in the present case is a ratchet wrench especially adapted for automobile use.

15 The present application is a division of our prior application, Serial Number 557,384, filed April 25, 1910. In that case the subject matter was directed particularly to the ratchet features of the wrench, while 20 in our present invention we shall particularly direct our attention to matters of extensibility.

It is the object of our invention to provide a wrench capable of various combinations and adjustments, making possible the use of powerful leverage on nuts, screws 25 and plugs in otherwise inaccessible places.

Throughout specification and drawings like reference numerals are employed to indicate corresponding parts and in the drawings we have shown a type of wrench which we have found well adapted for practical purposes and well suited to the requirements 30 of commercial manufacture.

35 In the drawings:—Figure 1 is a sectional view of a wrench stem and connections, illustrating the principles of our invention, Fig. 2 is a horizontal section of the wrench head through the stem, Fig. 3 is a central 40 sectional view of the wrench head with the locking ring removed and showing the clamping spring, Fig. 4 is a plan view of the ratchet socket piece, and Fig. 5 a detail of the clamping spring.

45 The wrench proper consists of circular head 1 having a radial neck 2. The head 1 is formed with a transverse bore on the bottom of which a shoulder 3 is left, while at the top is formed a channel or seat 4. 50 Within the neck 2 is a radial bore 5 within which is located a reversible pawl 6 adapted to fasten to a stem 7. A tubular handle 8 is threaded into the end of the radial neck 2 and within this handle a stem 7 is held hav-

ing its outer end milled, as indicated at 7¹ 55 and projecting slightly beyond the end of the handle.

The radial opening in the neck 2 is widened just above the transverse bore to form a shoulder 5¹ and against this shoulder 60 a ring 9 is set having two oppositely disposed notches 9¹.

The pawl 6 is pinned to the stem 7 by a pin 10 which projects slightly beyond the pawl so as to form an engaging point with 65 the notches 9¹ of the ring 9. This permits of the adjustment of the stem 7 in two opposite positions for direct and reverse motions. The stem 7 is held inward by a coiled spring 11 which abuts at one end against the 70 end of the tubular handle 8. At the other end it abuts against the rear side of the pawl 6.

Within the transverse bore of the head 1 is a ratchet piece 12 having external teeth 13 75 and a central internal squared socket 14 passing directly through it from side to side. This ratchet piece 12 is rotatably supported by the bearing head between the shoulder 3 and the ring or washer 4¹ which 80 is swaged in the groove 4.

A vertical squared opening 14 passes through the ratchet piece 12 and on one side of the opening is a vertical groove 14¹. On the upper and lower faces of the piece 12 85 adjacent to the groove are bored small recesses 15 which are preferably slightly slanted or tipped away from the opening 14, as will be seen by reference to Fig. 3. Within this groove 14¹ is located a bowed 90 leaf spring 36 of slightly less width than the channel 14¹ so as to be retained and guided therein. The spring 36 has at each end an ear 36¹ turned at an angle thereto. This ear is preferably of circular form to 95 fit a pair of recesses 15. The spring 36 will, therefore, lie within the groove 14¹ having its central bowed portion exposed within the bearing 14, thus affording a firm grip upon anything thrust within the socket.

100 While the combination with the catchet handle may be of a variety of constructions, we provide an extension member which consists of a stem 16 squared to fit the socket 14 of the ratchet. Upon this stem 16 is a 105 pair of jaws 17 having rounded ends. A stem 19 is provided having similar jaws 18 and the two sets of jaws 17 and 18 straddle

a cubical block 20 to which they are pivoted on bearings 21 and 22, each set being pivoted. This construction forms a very strong and flexible universal joint between the stem 16 and the shank 19.

On the squared end of the shank 19 is driven a squared sleeve 23 having a slot 24 cut through one wall within which a bowed spring 25 is held by a cover piece 26 swaged 10 into a groove surrounding the slot 24. As the spring projects through the inner face of the wall 23 it will frictionally grip anything thrust within the socket.

The stem 16 may be of any length desired 15 or corresponding stems may be provided of varied lengths. The stem 27 of the wrench member 28 is made of the same size as the stem 16 so that it may be inserted directly into the socket 14 or into the holder 23. On 20 account of the adjustability of the socket 14 with relation to the shank 16 or any similar shank, it will be seen that the ratchet can be adapted to a great variety of positions.

In use, the pawl 6 is set in either right or 25 left hand position, according to whether the nut is to be screwed or unscrewed. This is accomplished by pulling on the end 7¹ of the stem 7 and giving the stem a rotation of 180 degrees; the pawl will then assume the opposite phase and present its beveled end so that it will ride in the opposite direction. In each of its true positions it will be locked by the engagement of the pin 10 in the notches 9¹ of the ring 9.

35 The tool to be used is selected according to the nature of the work. If an outside nut is to be turned on or off the stem 27 of the wrench 28 might be inserted direct into the socket 14 of the ratchet piece 12. In doing 40 this, the spring 36 would be compressed within the groove 14¹, and to some extent the ears 36¹ would be slightly raised. They will not, however, be wholly disengaged from the recesses 15. We find in actual practice that 45 it is very easy to place the spring 36 in its position in the groove 14¹ with its ears in the recesses 36¹, but it is practically impossible without the assistance of tools to again remove it from this engagement.

50 If the work to be accomplished has to be reached through intervening parts, it is desirable to introduce a stem piece. This may be a plain stem piece or a joined piece. We have shown in Fig. 1 a stem piece including

between its ends a universal joint. In this 55 case, therefore, the stem 27 of the wrench 28 would be inserted within the socket 23, within which it would be held by the frictional engagement of the spring 25 exposed to the bottom of the slot 24. The ratchet piece 12 60 would be adjusted on the stem 16 at any position desired. On account of the frictional engagement of the spring 36 the stem 16 may similarly be pushed through the socket 14 and will be held at any point by 65 the frictional engagement of the spring.

Various modifications may be made in the construction and operation of our ratchet, the nature and variety of the tools, and in the manner of assemblage and use of the 70 same, all without departing from the spirit of our invention, if within the limits of the appended claims.

What we, therefore claim and desire to 75 secure by Letters Patent is:

1. A ratchet wrench comprising in combination a handle having a transverse socket therein, a stem member rotatably mounted through said socket and having an end of a size to fit said socket and having a wrench 80 socket at its opposite end, and an interchangeable wrench member of a size to fit either of said sockets.

2. A ratchet wrench comprising in combination a handle having a transverse socket 85 opening therein, an extension stem having a shank of the same size as said socket and having a wrench socket at its opposite end, and an interchangeable wrench member having a stem of a size to fit either of said 90 sockets.

3. A ratchet wrench comprising in combination a handle having a transverse socket opening in the ratchet piece thereof, an extension stem having a shank of the same size 95 as said socket and having a wrench socket at its opposite end, a universal joint between said shank and wrench socket, and an interchangeable wrench member having a stem of a size to fit either of said sockets. 100

In testimony whereof we affix our signatures in presence of two witnesses.
